UNITED STATES PATENT OFFICE

2,354,965

ELECTRICAL INPUT CONTROLLER

Hans J. Ostermann and Theodore A. Cohen, Chicago, Ill., assignors, by means assignments, to Wheeco Instruments Company, Chicago, Ill., a corporation of Illinois

Application July 31, 1940, Serial No. 349,626

3 Claims. (Cl. 200—33)

This invention relates to an improved current interruptor means for adjustably varying the power supply to an electric circuit without the power losses usually attendant upon the use of rheostats and the like.

The primary object of this invention is to provide such an interruptor which is rugged, simple of construction, efficient in operation and convenient of installation, renewal and repair.

Other and further objects of this invention will be more apparent hereinafter as the same becomes better understood from an examination of the specification and claims in conjunction with the accompanying drawings wherein:

Fig. 1 is a vertical sectional elevation, at the line 1—1 of Fig. 2, of a current interruptor and housing therefor and associated parts forming a self-contained unit, with parts omitted, embodying this invention;

Fig. 2 is a vertical sectional view taken at the line 2—2 of Fig. 1;

Fig. 3 is a vertical section, somewhat enlarged, and taken at the line 3—3 of Fig. 2;

Fig. 4 is a diagrammatic view showing the interruptor elements in circuit so as to deliver 100% of or full required power to the load;

Fig. 5 is a similar view showing the interruptor elements in circuit so as to deliver no current to the load;

Fig. 6 is an enlarged detail front view from the left of Fig. 1 showing the adjustable indicator mechanism.

Referring to the drawings more particularly, reference character 1 designates a front frame section cast to provide a central opening and mount for a ball bearing unit 2 and an integral rearwardly extending arcuate support 3 for a combined reduction gear and motor housing 4—5. A rear housing section 6 has an annular integral forwardly extending wall 7 which fits within an annular rearwardly extending peripheral flange 8 on the casting 1. A removable annular flange 9, shown in dotted lines in Figs. 1 and 2, may be provided for mounting the unit in a panel (not shown).

The ball bearing unit 2 rotatably supports a sleeve 10. The sleeve 10 carries, at one end, an integral circular manually rotatable cup shaped member 11 and, at its other end, a cam 12 for rotation therewith. A broken shaft 13 extends through the sleeve 10, permitting relative rotational movement between said shaft and sleeve, the other end of said shaft being mounted in a suitable bearing 14 in the reduction gear housing 4. A second cam 15 is mounted on the shaft 13, is

integrally formed with a coupling for the two sections of said shaft, is locked to said shaft section by set screws 16a and is adapted to be driven by the motor 5. The cam 15 also forms part of a friction clutch 17 having faces 18 and 19, face 19 being yieldably connected to cam 12 and rotatable therewith by means of pin 12a and compression spring 12b. Friction facing 18 is attached to cam 15 and rotatable therewith.

The outer end of shaft 13 has mounted thereon, for rotation therewith, a circular disk 21 which is graduated in two hundred equi-angular divisions arranged about its entire circumference. These graduations are visible, a predetermined number at a time, through a window 22 in a cover 23 in cup member 11. The window 22 has an index pointer 28 so that the cup shaped member 11 may be manually rotated to move cam 12 to any desired rotational position with respect to cam 15. The cams 12 and 15 are modified 180 degree cams, that is around half of their circumference they are high and the other half they are low.

Within the housing 1—6 and attached to casting 1 there is mounted a pair of single pole-double throw snap action switches 25 and 26 bolted in spaced relation by bolts 27 and spacer 28 and each provided with an operating roller 30 and 31 for contacting cams 12 and 15 respectively. These roller operated snap action switches are of a type well known in the art. The rotation of cams 12 and 15 move rollers 30 and 31 up and down to thereby open and close the contacts of the respective switches 25 and 26.

A terminal plate 32 having current conducting terminals 33 is mounted upon casting 1, within the housing 1—6, by suitable brackets 34 as shown in Fig. 2.

When it is desired to provide full required power for load 36 from line supply 37, the cup shaped member 11 is revolved manually to cause relative movement between the cams by virtue of slippage between clutch faces 18—19 to bring said cams to coincidental relative position shown in Fig. 4. In this position the indicator pointer 28 would read 100 on dial 21. With the cams 12 and 15 as shown, the switches 25 and 26 will have their contacts 25a and 25b and 26a and 26b closed for 180 degrees of rotation of shaft 13. The remaining 180 degrees of rotation of shaft 13 and said cams will cause switches 25 and 26 to reverse their contact positions to open contacts 25a and 25b and 26a and 26b and close contacts 25c and 25d and contacts 26a and 26c. Thus current will flow from line to load without interruption during full 360 degree revolution of shaft 13. The

50
55

rotation time of shaft 13 may be chosen as required but in the form shown is one revolution per minute and for the cam position shown current will flow for 100% of this time cycle.

In Fig. 5 is shown the obverse condition for 0% of the time cycle, wherein the cam 12 has been rotated 180 degrees with respect to cam 13 by manual operation of cup 11 to cause an indicator reading of zero on dial 21. With the cams as shown in Fig. 5, switch 25 has contact 25a and 25c closed and 25b and 26b open while switch 26 has contacts 26a and 26b closed and 26a and 26c open during 180 degrees of rotation of shaft 13. No current may flow from line 37 to load 38 during this time as the circuit is open. The same open circuit condition remains during the remaining 180 degrees of rotation of shaft 13 wherein switches 25 and 26 reverse their contact positions so that contacts 25a and 25b are closed, 25c and 26c are open with 25a and 26b open and 26a and 26c closed. Thus for the full 360 degree rotation of shaft 12 the circuit remains open and no current can flow to load.

Any intermediate position between these two extreme positions shown of 100% input and 0% input may be chosen by appropriate corresponding setting of the indicator assembly 11, 21 and 29. For example, should 50% be desired, cup 11 would be rotated so that pointer 29 would read "50" on dial 21 (Fig. 6), the cam positions would be such as to cause switches 25 and 26 to maintain the current flow circuit to load 38 closed for 50% of the cycle and open for the remaining 50% of the cycle. Thus if shaft 13 has a rotational cycle of 1 R. P. M. the circuit will be closed for 15 seconds during the first 180 degrees of rotation and open for 15 seconds during this 180 degrees rotation, closed again for 15 seconds and open again for 15 seconds for the remaining 180 degrees of rotation. In a 360 degrees rotation there will be two closed circuit periods and two open circuit periods, each period 15 seconds long.

It will be seen that the power from line to load may be varied without loss by use of the afore-described apparatus because power consumed in a load is the product of watts and time, e. g. watt hours used, and the input may be reduced by fractionally reducing the time portion of the product of watts and time.

The circuit may be seen to be a variety of three way switching. It is obvious that the circuit may be otherwise arranged than as shown in Figs. 4 and 5, for instance the connections between contacts 26b and 25b and between contacts 25c and 26c may be wired so that a connection is made

between contacts 25b and 25c and another connection between contacts 25b and 26c without disturbing the function.

In addition the ruggedness and simplicity of construction of the apparatus described as well as the manner and convenience of its use, installation and accessibility for inspection, renewal and repair, as well as other advantages, will be apparent without further description.

We are aware that many changes may be made and details varied without departing from the principles of our invention and we therefore do not wish to be limited to the details shown and described.

We claim:

1. In an apparatus of the character described, a pair of cams, means for driving the same at a predetermined rate of speed, manually operated means for adjusting the relative position of one cam with respect to the other so as to obtain an adjustable range of zero to 100% input to load and cooperating switch means operable by said cams.

2. In an apparatus of the character described, 25 a pair of cams, means for driving same at a predetermined rate of speed, manually operated means for adjusting the relative position of one cam with respect to the other so as to obtain an adjustable range of zero to 100% input to load and cooperating switch means operable by said 30 cams, said switch means including switches interconnected so that the load circuit is completed during such portions of the rotating cycle in which the switches are in corresponding 35 positions and open during such portions of the rotational cycle in which the switches are in non-corresponding positions to thereby control the ratio of time on to time off of input to load.

3. In an apparatus of the character described, 40 a pair of cams, means for driving same at a predetermined rate of speed, manually operated means for adjusting the relative position of one cam with respect to the other so as to obtain an adjustable range of zero to 100% input to load and cooperating switch means operable by said 45 cams, said switch means including switches interconnected so that the load circuit is open during such portions of the rotating cycle in which the switches are in corresponding positions and completed during such portions of the rotational 50 cycle in which the switches are in non-corresponding positions to thereby control the ratio of time on to time off of input to load.

HANS J. OSTERMANN.
